Dudley P. Combs, Newton, Iowa, assignor to The Maytag
Company, Newton, Iowa, a corporation of Delaware

Application January 10, 1958, Serial No. 49,191

Term of patent 14 years

(Cl. D49—1)

Fig. 1.

Figure 1 is a perspective view of a control panel for a laundry appliance embodying my new design;

Figure 2 is a front elevation of the control panel shown in Figure 1;

Figure 3 is a side elevation of the control panel of Figure 2 taken along line 3-3 thereof;

Figure 4 is a sectional view of the control panel of Figure 2 taken along line 4-4 thereof; and,

Figure 5 is a sectional view of the control panel of Figure 2 taken along line 5-5 thereof.

The dominant features of my design reside in the portions shown in full lines.

I claim:

The ornamental design for a laundry appliance control panel, substantially as shown and described.
